FOREIGN PATENT DOCUMENTS

WO WO 00/06420 2/2000

Primary Examiner — Katrina N Gonzalez(74) *Attorney, Agent, or Firm* — Thomas A. O'Rourke; James Bongiorno; O'Rourke IP Law, PLLC(57) **CLAIM**

The ornamental design for a light bar as shown and described.

DESCRIPTION

FIG. 1 is a perspective view of a light bar illustrating the new design.

FIG. 2 is a top view thereof.

FIG. 3 is a front view thereof; the rear view is identical to the front view shown in FIG. 3.

FIG. 4 is a bottom view thereof; and,

FIG. 5 is a right side view thereof; the left side view is identical to the right side view shown in FIG. 5.

The broken lines shown in the drawings depict portions of the light bar that form no part of the claimed design.
